UNITED STATES PATENT OFFICE.

SEBASTIAN ZIANI DE FERRANTI, OF LONDON, ENGLAND.

HEATING DEVICE.

No. 867,576.

Specification of Letters Patent.

Patented Oct. 8, 1907.

Application filed December 28, 1905. Serial No. 293,672.

To all whom it may concern:

Be it known that I, SEBASTIAN ZIANI DE FERRANTI, a subject of the King of Great Britain and Ireland, residing at 31 Lyndhurst road, Hampstead, London, England, have invented certain new and useful Improvements in and Relating to Heating Devices, of which the following is a specification.

My invention relates to elastic fluid turbines and more especially to the efficient utilization of heat in turbines employing superheaters and resuperheaters.

Examples of the types of turbines to which my improvements are applicable are found in my prior specifications, Serial Nos. 179407, 211838 and 232525.

I have found that where a limited drop of temperature only is available, as for example, in resuperheater furnaces such as are described in my specification, Serial No. 179407, great difficulty arises in getting the required amount of heat imparted to each of the resuperheater elements; and my invention has for its object to enable this difficulty to be overcome without requiring to provide abnormal heating surfaces in the resuperheaters for the later stages of the expansion.

My invention consists broadly in disposing the heat absorbing apparatus (such as the resuperheaters) through which the steam flows in series, in parallel or multiple parallel in relation to the flow of the gases from which the heat is to be absorbed, so that each element may be subjected to the best drop of temperature available, viz., that drop of temperature which is best suited to secure efficient abstraction of heat.

My invention also consists in the apparatus and combinations of parts hereinafter indicated.

Referring now to the accompanying drawings which illustrate my invention and form part of my specification, Figure 1 is a cross section of a furnace having superheating and resuperheating elements arranged therein and working in conjunction with a stage turbine. Fig. 2 is a longitudinal section through the furnace shown in Fig. 1. Fig. 3 is a sectional plan of a modification of the arrangement shown in Figs. 1 and 2 with the turbine omitted. Fig. 4 is a longitudinal elevation partly in section of a modification of the invention in which the superheater and resuperheater elements are disposed in tiers, while Fig. 5 is a corresponding section on the line A B of Fig. 4.

The drawings are of a purely diagrammatic nature throughout and are not to be taken as working drawings.

In carrying my invention into effect according to one form as applied in conjunction with turbines of the type described in my specification, Serial No. 179407, I provide such a turbine, A, divided into stages as indicated by the dotted lines and I place resuperheater elements, a, in parallel in the furnace, b. In those circumstances where a superheater ele-

ment, c, is included in the plant I prefer to arrange it along with the resuperheater elements in the furnace, b, so that all the heat absorbing elements referred to are arranged in parallel with regard to the path of the heating gases from the furnace, b, as indicated by the arrow in Fig. 2. In circumstances where a large number of superheating or resuperheating elements is employed I may arrange them in multiple parallel.

In order to efficiently absorb the balance of available heat remaining in the furnace gases after passing through the heat absorbing elements I preferably arrange a section of a boiler, d, or an economizer for water or air or both directly behind them for this purpose. Thus steam generated in the boiler, d, passes by way of the pipe, e, to the superheater, c, and thence through the pipe, f, to the first stage of the turbine. The steam after expansion in this stage returns by the pipe, g, to the furnace where it is resuperheated and passes by way of the pipe, h, to the second stage of the turbine, this process being repeated as often as desirable.

According to a modification of the arrangement shown in Figs. 1 and 2 I sometimes prefer to separate the superheater elements, c, as shown in Fig. 3 by partition walls, i, and provide dampers or valves, j, for controlling the flow of the gases through each compartment. Again, I may arrange the heat absorbing elements in groups so that they are disposed in parallel in tiers. Such an arrangement is illustrated in Figs. 4 and 5, where I dispose first a bank of tubes, k, of, say, the superheater, then a bank of tubes, l, of the first resuperheater, then a bank of tubes, m, of the second resuperheater, repeating these banks, k, l, and m, as often as is required to give the desired heating surfaces. All the banks of the superheating element are connected by means of boxes, n, and tubes, o, while the first and second resuperheater tubes are connected respectively by drums, p, q, and connecting pipes, r, s. With this arrangement substantially the same effect is obtained as with the heat absorbing elements arranged as already described with reference to Figs. 1, 2 and 3.

The course of the steam through the modification of my invention just described is, as follows:—Passing from the boiler, d, by way of the pipe, t, it enters the drum, n, and passes through the superheater tubes, k, and thence by way of the pipe, u, to the first stage of the turbine, A. After expansion in this stage it passes by way of the pipe, v, to the drum, p, of the first set of resuperheater tubes, l, and after passing through these and the tube, r, traverses the second corresponding set of resuperheater tubes, l, and returns through the pipe, w, to the second stage of the turbine. This cycle of operations is repeated by way of the second set of resuperheater tubes, m, with the corresponding drums, q, in a manner that will be clear from the drawing without further description.

110

I find that if the tube surfaces are correctly proportioned over a given load they will be practically right over a wide range of loads since the quantity of the products of combustion passing through the flue, the coal burned, and the steam generated, all vary together.

Having now described my invention; what I claim as new and desire to secure by Letters Patent is:—

1. In combination; a plurality of turbine chambers; conduits connecting said chambers in series, certain of said conduits having operative portions exterior to said chambers; flue means through which hot gases flow, certain of said conduit operative portions standing in the same operative relation to different chambers being disposed side by side across said flue means in portions of said hot gases at substantially the same temperature.
2. In combination, a plurality of turbine chambers; a superheater connected to the inlet of the first of said chambers; conduits connecting said chambers in series, certain of said conduits having operative portions exterior to said chambers; flue means through which hot gases flow, certain of said conduit operative portions together with said superheater being disposed side by side across said flue means in portions of said hot gases at substantially the same temperature.
3. In combination, a plurality of turbine chambers; conduits connecting said chambers in series, certain conduits having operative portions exterior to said chambers; flue means through which hot gases flow, certain of said conduit operative portions standing in the same operative relation to different chambers being disposed side by side across said flue means in portions of said hot gases at substantially the same temperature; boiler elements also disposed in said flue means and on that side of said conduit operative portions from which said hot gases flow.
4. In combination, a plurality of turbine chambers in which working fluid undergoes successive expansions; a superheater connected to the inlet of the first of said chambers; together with means for rendering the aggregate expansion through certain of said chambers on the whole substantially isothermal, said means including conduits connecting said certain chambers, said conduits having operative portions exterior to said chambers and including also flue means through which hot gases flow, said conduit operative portions being disposed in parallel in said flue means as regards the flow of said hot gases therethrough.
5. In combination, a plurality of sets of heat absorbing elements, through which sets fluid passes, the corresponding elements of different sets being arranged cyclically in

a certain order together with duct means through which a heating medium passes, said heat absorbing sets being disposed in parallel in said duct means as regards the flow of 50 said heating medium therethrough.

6. In combination, a plurality of turbine chambers; conduits connecting said chambers in series, certain of said conduits having operative portions exterior to said chambers; flue means through which hot gases flow, certain of 55 said conduit operative portions standing in the same operative relation to different chambers being disposed in said flue means in portions of said hot gases at substantially the same temperature.

7. In combination, a plurality of turbine chambers; a 60 superheater connected to the inlet of the first of said chambers; conduits connecting said chambers in series, certain of said conduits having operative portions exterior to said chambers; flue means through which hot gases flow, certain of said conduit operative portions together 65 with said superheater being disposed in said flue means in portions of said hot gases at substantially the same temperature.

8. In combination, a plurality of turbine chambers; conduits connecting said chambers in series, certain conduits 70 having operative portions exterior to said chambers; flue means through which hot gases flow, certain of said conduit operative portions standing in the same operative relation to different chambers being disposed in said flue means in portions of said hot gases at substantially the 75 same temperature; boiler elements also disposed in said flue means and on that side of said conduit operative portions from which said hot gases flow.

9. In combination, a plurality of turbine chambers in which working fluid undergoes successive expansions; a 80 superheater connected to the inlet of the first of said chambers; together with means for rendering the aggregate expansion through certain of said chambers on the whole substantially isothermal, said means including conduits connecting said certain chambers, said conduits having operative portions exterior to said chambers and including also flue means through which hot gases flow, said conduit operative portions and said superheater being disposed in 85 parallel in said flue means as regards the flow of said hot gases therethrough.

In testimony whereof I have signed my name to this specification in the presence of two subscribing witnesses.
